Application May 2, 1933, Serial No. 669,036
In Germany May 6, 1932

7 Claims. (Cl. 112—27)

This invention relates to a method of transferring stockings worked on flat hosiery frames.

It is known to produce stockings by inserting in a leg worked on a flat hosiery frame and being integral with the sole portions, the instep and the toe heel parts that have been worked separately. The sole portions then connect directly with the high heel portions and the instep forms the continuation of the central portion of the leg positioned between the high heel parts. To insert heel portions in the stocking it is customary to separate the sole portions from the high heel parts by incisions and to transfer the high heel portions beside the sole portions in the direction of their courses to the transfer needles of a looping machine. Each transfer in the course requires, however, a plurality of top rows over the edge to be transferred, so that the latter which will easily curl up may be conveniently handled and properly transferred. The result is that after undoing these top rows there will remain between the transfer line of the high heel parts and that of the sole parts a relatively broad gap which after the linking of the heel portions will form a slit on both sides above the heel angles, and these slits must be united by sewing later on. Apart from the fact that such a stocking is somewhat unsightly in the heel angles, it suffers from the drawback that the strength of the highly stressed heel angles is reduced.

It has been proposed already to overcome these troubles by working in the requisite top rows while stopping the working of the central leg portion, but this would involve a special construction of a flat hosiery frame, such as subdivided needle bars and the like, not found in ordinary machines.

According to the invention, in order to insert separately produced heel portions in a stocking worked on a flat frame and having a leg integral with the sole portions, the instep and the toe, the stocking is properly transferred to two closely superposed rows of transfer needles at the point where the sole portions have to be separated from the high heel portions for inserting the heel portions, whereupon separation of the sole portions from the high heel portions is effected between the two transfer rows.

This method can be applied also to such stockings in which the heel portions with their initial course have been connected already on the frame with the body of the stocking, so that subsequently only the inner longitudinal edges of the heel portions have to be united with the body of the stocking structure. In every instance, the trans-

fer needles to which the sole portions have been transferred are preferably brought inside beside the transfer needles holding the high heel portions into a common plane whereupon the inner longitudinal edges of the heel portions are transferred to the transfer needles of the sole portions. Transfer of the stocking is preferably carried out on a transfer device or a linking machine from whose row of transfer needles parts may be swung out 180°, so that these swung-out parts will be 10 positioned above the adjacent needles of the transfer needle row.

Two embodiments of the invention are illustrated in the accompanying drawings, in which Figures 1 and 2 show how the heel portions with 15 their initial courses are connected already on the flat frame with the body of the stocking; Fig. 3 shows how a stocking according to Fig. 2 is transferred above the fixing points of the heel portions to two closely superposed transfer needle 20 rows; Fig. 4 shows how after the separation of the high heel portions from the sole portions the transfer needles of the latter are brought on the same plane with the transfer needles of the former; Fig. 5 shows how afterwards the inner 25 longitudinal edges of the heel portions are transferred to the transfer needles of the sole portions; Fig. 6 shows how a stocking structure is transferred without heel parts connected thereto on a flat hosiery frame; and Figs. 7 and 8 30 are, respectively, a front and top view of a portion of the transfer needle row of a looping machine.

Referring to the drawings, the stocking structure 1 is transferred correctly, at the point where the insertion of the heel portions 2 requires separation of the high heel portions 3 from the sole portions 4, to two closely superposed transfer needle rows 5, 6, 6', whereupon by suitable means, such as a very thin knife, separation of the high 35 heel portions 3 from the sole portions 4 takes place on the chain dotted line in Fig. 3. It is therefore no longer necessary to interpose additional top courses between the two transfer rows, only a certain separating course being needed, 40 and both the end course of the high heel portions 3 and the initial course of the sole portions 4 will thus be correctly held without the usual loss 45 of courses. The transfer of the parts 3 and 4 may be effected directly to the needles of a correspondingly arranged looping machine or to the needles of a special transfer device, in which 50 case the structure 1 is transmitted to the looping machine for the purpose of linking on the heel portions 2.

The transfer points of the needle row 6, 6' of the sole portions 4, after separation of the sole portions 4 from the high heel portions 3, will then be simply brought inside beside the transfer points 5 of the high heel portions 3, so that all transfer points are on the same plane, as indicated in Figs. 4 and 7. This can be done by hand by means of two small transfer bars with which the needles for the rows 6, 6' are provided. It is, however, advisable to employ a specially formed transfer device whose transfer needle rows 6, 6' for the sole portions 4 are arranged on fastening means capable of moving 180°, so that the transfer needles of these movable parts 10 may be brought from a plane common with the needles for the high heel portions 3 above the transfer needles of the high heel needle row 5. If the transfer is to take place directly to a looping machine, the transfer needle row thereof 15 should be correspondingly formed. The needles of the transfer row 5 for the high heel portions 3 are then secured to the usual bar 7, but the needles of the transfer row 6, 6' are attached to the fastening means 8, Figs. 7 and 8, which can 20 be swung out of the needle row to the extent of 180°. The arrangement is such that the parts 8 will be between the needles of the transfer row 5 when all needles are on the same plane. The arms 9, 10 insure the mobility of the parts 8.

30 After the transfer needles of the needle row 6, 6' of the sole portions 4 are brought on the same plane with the needles of the transfer row 5 in the manner described, the inner longitudinal edges 11 of the heel portions 2 are then transferred to the needles of the row 6, 6' so as to permit linking of these edges.

By means of the method and device described it is possible to transfer the separately worked heel portions 2 both on their initial course 12 and on their inner longitudinal edges 11. Then the foot with toe, instep and sole portions is worked on directly to the leg and the entire structure transferred as stated. After separation of the high heel portions 3 from the sole portions 4 the transfer points of the row 6, 6' are brought on the same plane with the transfer points of the high heel portions 3. Then the initial courses 12 of the heel portions 2 are transferred to the transfer needles of the needle row 5, and their inner longitudinal edges 11 to the needles of the transfer row 6, 6'. If transfer takes place directly to a looping machine, the heel portions 2 may be linked in directly.

It is further possible to transfer the heel portions 2 with their initial courses 12 to the needles of the machine producing the stocking structure and to bring them during the production of the leg under the knocking over member 13 as shown in Fig. 1. If the leg is then finished with its heel portions 3, the heel portions 2 are brought on the member 13 and thus during the further working of the foot bound into the body of the structure 1, Fig. 2. This stocking structure 1 is then transferred slightly below its heel joining points 12 to the needle rows 5, 6, 6', Fig. 3, whereupon separation of the high heel from the sole portions takes place again. After the transfer points of the sole portions 4 have then been brought on a plane with those of the high heel portions 3, as shown in Fig. 4, the inner longitudinal edges 11 of the heel portions 2 may be transferred also to the needles to which the sole portions 4 have been transferred. Only the inner longitudinal heel edges 11 will then be linked with the initial sole courses. The end

course of the high heel portions 3 is finished off only to prevent unravelling up to the binding-in point of the heel portions 2. This method is superior to the one described before in so far as the points of junction of the high heel portions 3 with the heel portions 2 are not conspicuously visible.

I claim:—

1. A method of transferring a stocking structure worked on a flat frame and having sole portions directly connecting with the high heel portions for the purpose of inserting separately worked heel portions, consisting in properly transferring the stocking structure at the point where prior to inserting the heel portions the sole portions have to be separated from the high heel portions to two closely superposed transfer needle rows, and separating thereafter the sole portions from the high heel portions between the two transfer rows. 20

2. A method according to claim 1, consisting in transferring a stocking, whose heel portions up to the finishing of the high heel portions have been placed under the knocking over member of a flat hosiery frame and connected with the body of the stocking by being brought on the said member, slightly below the connecting point of the heel portions to the two closely superposed transfer needle rows. 25

3. A method according to claim 1, consisting in bringing the transfer needles to which the sole portions are transferred inside beside the transfer needles holding the high heel portions on a common plane, and transferring the inner longitudinal edges of the heel portions to the transfer needles of the sole portions. 35

4. A transfer device for a flat hosiery frame, comprising a transfer needle row having parts capable of being swung out of the needle plane to the extent of at least 180° to cause the needles 40 of said parts to lie horizontally and above the adjacent needles of the transfer needle row, the needle plane of said swung-out parts extending then parallel to the needle plane of the transfer needle row. 45

5. A looping machine for manufacturing hosiery comprising a transfer needle row having parts capable of being swung out of the needle plane to an extent of at least 180° to cause the needles of said parts to lie horizontally and above 50 the adjacent needles of the transfer needle row, the needle plane of said swung-out parts extending then parallel to the needle plane of the transfer needle row.

6. A transfer device for a flat hosiery frame 55 comprising a transfer needle row, and means for mounting parts of said row so that they are capable of being swung out of the needle plane to the extent of at least 180° to cause the needles of said parts to lie horizontally and above the adjacent needles of the transfer needle row, the needle plane of said swung-out parts extending then parallel to the needle plane of the transfer needle row. 60

7. A looping machine for manufacturing 65 hosiery comprising a transfer needle row, and means for mounting parts of said row so that they are capable of being swung out of the needle plane to the extent of at least 180° to cause the needles of said parts to lie horizontally and above 70 the adjacent needles of the transfer needle row, the needle plane of said swung-out parts extending then parallel to the needle plane of the transfer needle row.
